BASCULE BRIDGE LOCK

Harold H. Gilbert, San Carlos, Calif.

Application September 12, 1949, Serial No. 115,225

5 Claims. (Cl. 14—41)

1

This invention relates to bridge locks and particularly to center shear locks for double leaf bascule bridges.

Double leaf bascule bridges are well-known to the civil engineering profession and their advantages are well-known to those skilled in the art. However, and as is also well-known to those skilled in the art, they are subject to certain shortcomings, one of the most important of which is the problem of providing a suitable center shear lock to carry a live load such as a load imposed by a moving crane or train, or by vehicular traffic. In the past double leaf bascule bridge shear locks have consisted of a pair of shear pins which ran longitudinally of the bridge. Certain mechanical difficulties were encountered as, for example, the difficulty of aligning the two leaves of the bridge both vertically and horizontally. In addition, such devices provided only a single shear and required a substantial mass and cross-section to meet the strain and forces encountered in bridges of this character.

It is an object of the present invention to provide a double leaf bascule bridge center shear lock which will provide a double shear.

It is a further object of this invention to provide a device of this character which is simple to operate, which provides minimum clearance vertically about the shear pin and the face of the groove receiving the same and which at the same time presents maximum load bearing surfaces for the transfer of the load from one leaf of the bridge to the other.

It is a further object of this invention to provide a double leaf bascule bridge center shear lock which allows free movement of the leaves of the bridge longitudinally with respect to one another during expansion and contraction.

It is a further object of this invention to provide a free-floating aligning member adapted to receive and accommodate the shear lock pin in spite of any small differences of angular alignment between the adjacent leaves of the bridge.

Other objects and advantages of the invention will appear from the following description taken in conjunction with the accompanying drawings in which:

Figure 1 represents a plan view of the adjacent ends of the two leaves of a double leaf bascule bridge in which my invention is incorporated; one half width of the bridge is shown only, a similar arrangement being provided on the other half of the bridge;

Figure 2 represents a view of the end of the bascule leaf taken along the line 2—2 of Figure 1;

2

Figure 3 represents an enlarged cross section taken along the line 3—3 of Figure 2;

Figure 4 represents a cross section taken along the line 4—4 of Figure 3;

5 Figure 5 represents a cross section taken along the line 5—5 of Figure 4; and

Figure 6 represents an exploded view of the device shown in Figure 3.

10 As is shown generally in Figures 1 and 2, adjoining leaves 10 and 11 of a bascule type bridge join at their adjacent ends and are locked together by a suitable device, in this case called a shear lock, to transfer the live load shear from one leaf to the other.

15 As is particularly shown in Figure 1, the leaf 10 of the double leaf bascule bridge illustrated herein carries movable lock pins 12 and their operating mechanism, together with what might be termed the female or receiving member 13 of the locking mechanism. The portion 11 of the double leaf bascule bridge carries the male portion 14 of the locking mechanism.

20 The shear pin 12 consists generally of a pin, rectangular in cross section, as shown. As is shown in Figures 1, 2 and 4, pin 12 is provided with a rounded end 16 and the other end is adapted to be secured to a connecting rod 17 by means of a suitable wrist pin arrangement 18. It is, of course, understood that in the construction of particular bridges certain types of connecting elements may be desirable and may be utilized without departing from the spirit of this invention. The pin 12 is adapted to reciprocate within a slot or keyway 21 formed generally as shown 25 in Figures 3 and 6.

25 The slot 21 is formed by a recess in the casting 22 which in turn is suitably secured to the leaf 10 by means of bolts or by welding or any other suitable means as expediency may dictate. A 30 cap 23, in the form of a plate, is provided to overlie a portion of the slot in such a manner as to retain the pin 12 in the slot. The cross section of the slot 21 is substantially identical with the cross section of the pin 12, all as shown in Figures 35 3 and 6 particularly.

35 In addition to the horizontal recess 21, the casting 22 is provided with a vertical slot or channel 26 generally as shown in Figures 1, 2, 4 and 5. As is shown in Figures 1, 2, 4 and 5, the 40 vertical channel 26 is slightly flared at both its upper and lower ends, but at the point at which it intersects horizontal slot 21, it is substantially the same width as the member 14.

45 The male member 14, as is particularly shown 50 in Figures 1, 5 and 6, consists generally of a cast-

ing 28 which may be suitably secured to the leaf 11 of the double leaf bascule bridge herein described. The member 14 is adapted to be received within the vertical slot 26 in the member 13 and by virtue of the flared shape of the slot 26 is adapted to be centered therewithin when the leaves are in proper position for the reciprocation and actuation of the shear pin 12.

Casting 28 is also provided with a horizontal circular recess 31 as shown. I have provided a 10 pair of aligning discs 32 and 33 which are adapted to be accommodated within the recess 31, and which are retained therein by virtue of their shape which is substantially circular, as is particularly shown in Figure 6. The discs 32 and 33 may be bolted together in any suitable manner and thus they become, in effect, one loosely rotatable mounted member within the recess 31. The discs 32 and 33 are provided with a common keyway 34 which is in substantial registry with a 20 keyway 36 in the casting 28. The keyways 34 and 36 loosely accommodate a key 37. The key 37 permits a slight rotation of the discs 32 and 33 within the circular recess 31. This assembly provides a floating alignment disc and allows a certain amount of deflection and adjustment for purposes to be more fully hereinafter described.

The means for actuating the pin 12 consists generally of a motor 41 which, through identical drive shafts 42 and suitable gear reduction devices 43, operates a pair of crank wheels 44.

Connecting rods 17 are suitably secured to the crank wheels 44 whereby, upon rotation of the crank wheels 44, reciprocating motion is transmitted to the pin 12 to either advance the same to the left, as shown in Figure 1, or advance the same to the right. A suitable limit switch 46 is provided to permit only 180° rotation of the wheels 44.

At this point it should be made clear that all of the assembly to the left of the motor 41, as shown in Figures 1 and 2, is duplicated on the other side, or to the right of the motor 41 to provide a pair of pins 12 and their receiving elements 13 and 14, whereby suitable locking is provided at each side of each of the leaves of the double bascule bridge herein described.

The motor 41 and the gear reduction unit 43 may be of any particular type which may be advantageous with respect to the particular type of construction to which my invention is applied.

Operation of the device may briefly be described as follows: Let it be assumed that both leaves of the bridge are down and that traffic is passing over the roadway 10a. Then let it be assumed that it is desirable to raise the leaves 10 and 11 of the bridge. The electric motor 41 is actuated and the crank wheels 44 are actuated one-half a revolution. This rotary motion of the crank wheels 44 is translated by the connecting rod 17 to the pin 12 and the same is moved to the right, as shown in Figures 1 and 2, in such a manner that it is withdrawn entirely from the male portion 14. It must be borne in mind that similar action is simultaneously occurring on the other side of the bridge. When this is done the bridge is free to be raised. The bridge is then raised. When the reason for the bridge having been raised has terminated, the two leaves are then lowered. As the two ends of the members 10 and 11 approach each other, the members 13 and 14 will likewise approach each other. Because of the double flare of the vertical slot 26 in the casting 22, the male member 14 will be urged into the position generally shown in Figures 2 and 4, that is, the position at which the

5 same is centered with respect to said slot, and consequently to the leaf 10 of the double leaf bascule bridge. When the members 13 and 14 are substantially in the position shown in Figures 2 and 4, the electric motor 41 is again actuated and the crank wheels 44 are again rotated. Rotary motion of the crank wheels 44 will, at that time, cause the pin 12 to be moved to the left, as shown in Figures 1 and 2. Because of the rotatable disc constructions 32 and 33 and because of the rounded end 16 of the pin 12, the pin will be advanced through the slot 31. The rotatable discs 32 and 33 will permit slight deflection, depending upon the relative sizes of the keyways 34 and 36 and the key 37. At any rate, as the pin 16 is advanced through the slot 31, the two discs 32 and 33 will be deflected slightly to accommodate themselves to the pin 12. The pin 12 will then be farther advanced through the slot 21 in the casting 22 and will be urged to the position shown in Figures 1, 2 and 4 and will provide a double shear between the members 13 and 14.

25 In addition, the rotatable discs 32 and 33 will permit a pin 12 to be received within the slot 31 when the adjacent ends of the leaves of the bridge are either slightly above or slightly below the horizontal. By this I mean that it is not essential that the two leaves of the bridge meet in a predetermined plane prior to their being locked together by the pin 12. The difference of a few inches above or below the preferred horizontal plane will not prevent the bridge being locked, as has previously been described.

30 It will be obvious from the foregoing that I have provided a suitable double shear pin construction which has numerous substantial advantages over present types of construction.

In the first place I have provided a pin which in turn provides a double shear rather than a single shear for a live load.

35 In the second place I have provided a female portion which is outwardly flaring in both directions whereby regardless of which leaf 10 or 11 of the double leaf bascule type bridge comes down first, the other will center itself properly with respect thereto in a vertical plane. In addition, I have provided a rotatable type of self-aligning disc construction upon the male member to allow for slight deflection and to prevent jamming of the pin upon operation of the pin should one or the other of the members 13 or 14 be slightly out of perfect angular alignment.

40 I claim:

1. In a device of the character described in which two unsupported load bearing members meet, a shear pin on one of said members adapted to be moved transversely with respect thereto, means for receiving said pin on said other member, said means for receiving said pin comprising a loosely mounted member provided with a transverse slot.

45 2. In a bascule bridge construction, a pair of pivoted bridge members whose ends are adapted to meet when the bridge is in lowered position, a lock for said bridge members comprising a pair of pins, each of said pins being slidably mounted on one of said members, a pair of spaced pin guide supports mounted on said member and receiving said pins when they are moved transversely with respect thereto, a pair of means on the other member each of which is adapted to be positioned in a slot in one of said guide supports and to receive one of said pins, said means including a pair of loosely mounted members

having a slot to receive said pins and adapted to accommodate themselves with respect to said pins when said pins are received therein.

3. In a device of the character described in which two unsupported load bearing members meet, means for locking said members against vertical movement comprising a slidable shear pin on one of said members and adapted to be moved transversely with respect thereto, a pair of spaced guide support members mounted on said one member and adapted to receive said pin, means for receiving said pin on said other member, said last-named means for receiving said pin comprising a loosely mounted member on said second member provided with a slot which is adapted to accommodate said pin when said pin is moved into engagement with said guide support members.

4. In a device of the character described in which two unsupported load bearing members meet, means for locking said members together against vertical movement comprising a plurality of double shear pins slidably mounted on one of said members and adapted to be moved transversely with respect thereto, means for receiving each of said pins on said other member, each of said means for receiving said pins comprising a loosely mounted member on said second member provided with a slot which is

adapted to accommodate said pins and which is open on the side adjacent said first named member.

5. In a double leaf bascule bridge construction, a center shear lock comprising a member fixed to the end of one of said leaves and slotted both vertically and horizontally, a second member fixed to the end of the other of said leaves and slotted horizontally, said second member being adapted to be received within the vertical slot in said first member, a loosely mounted disc member carried by said second member and serving to adjustably define the positioning of the horizontal slot in said second member, and means for locking said members against vertical shearing movement including a shear pin movable into and out of engagement with the horizontal slot in said first member and said disc in a direction transversely of said bridge leaves.
